COTTON DOFFING ASSEMBLY

Robert S. Radow and Robert E. Bennet, Dayton, Ohio, assignors to The Dayton Rubber Company, Dayton, Ohio, a corporation of Ohio

Application September 11, 1956, Serial No. 609,238

13 Claims. (Cl. 56—41)

This invention relates to doffer assemblies and more particularly to an improved doffer disc applicable for use in removing cotton from the picker spindles of cotton picking machines. The invention further contemplates an improved method for providing doffer assemblies.

Various constructions have been proposed for doffer assemblies in the prior art, but the doffer discs or plates employed to date have been relatively inflexible and subject to cracking and splitting. The picker spindles of cotton machines generally have varying accumulations of cotton thereon and it is recognized that a balanced uniform engaging relation between the picker spindles and doffer lugs on the disc elements is practically impossible. Accordingly, as the doffer disc unit is applied to the spindles, the doffer lugs thereon are subjected to varying loads as they are met with the varying accumulations on the spindles. These varying loads on the doffer pads or lugs have repeatedly caused not only rapid disc deterioration from shock effects but also have resulted in the doffer pads being torn from the disc portion in many instances. This is due mainly to the resistance of the relatively inflexible disc and poor methods of connecting the disc and doffer lugs. Efforts to correct these difficulties have been made by providing doffer pads of a flexible nature on a metal backed or a hard rubber disc base. However, this has not proved to be the solution to the problem since the manner of fabricating such doffer assemblies has still rendered the doffer pads subject to being stripped from the doffer disc when heavy loads are applied, a frequent occurrence when using the doffer assembly.

The subject invention offers a solution to the above problems and provides a doffer assembly of an improved nature that incorporates the doffer pads in such manner as to prevent them from breaking away from the doffer disc irrespective of the load or of the load variation on the pads as they are applied to cotton picking spindles of cotton picking machines. The invention in particular affords a flexible, yet strong doffer disc unit of a composite nature having doffer pads integrally molded thereto and connected in circumferentially spaced relation on one face thereof in a manner that affords greater flexibility to the doffer pad with increased strength and resistance to load thereon. Both the pads and the disc assembly are flexible while being sufficiently strong to resist any permanent deformation or distortion thereof in use. Increased flexibility with corresponding increased strength of the doffer assembly thus provided insures against cracking and tearing of the doffer assembly in its various component parts. The doffer assembly is completely integral in accordance with the invention.

An object of the invention is to provide a new and improved doffer assembly.

Another object of the invention is to provide the improved method of fabricating doffer assemblies.

A further object of the invention is to provide an improved doffer assembly wherein both the doffer disc and the doffer pads are of a flexible nature so that they may

2

each accommodate a portion of the load applied to the doffer pads and protect the pads and the doffer assembly against damage thereby.

Another object of the invention is to provide a novel method of molding doffer pads into a doffer disc so as to provide increased strength, stability and life to the doffer pads in use.

Another object of the invention is to provide an improved method of fabricating doffer assemblies of rubber and rubberized fabric to prevent cracking therebetween.

A further object of the invention is to provide an improved disc unit for a doffer assembly.

Another object of the invention is to provide a doffer assembly and method for making the same possessing the advantageous structural features, the inherent meritorious characteristics, and the improved mode of operation described herein.

With these and other objects more fully described in the specification, the invention consists of the features of construction, the parts and combinations thereof, and the mode of operation and method of fabrication as herein-after described or illustrated in the accompanying drawings or their equivalents. The above objects are carried out by providing a doffer disc assembly in which the disc is a sandwich of flexible rubber with a fabric layer on each face, and flexible pad integral with one face of the disc.

Referring to the drawings wherein is found the preferred but not necessarily the only form of embodiment of the invention:

Fig. 1 is a perspective view of the doffer assembly according to the invention.

Fig. 2 is a plan view of the assembly.

Fig. 3 is a cross-sectional view of the assembly of Fig. 2 taken along line 3—3 thereof.

Fig. 4 is an enlarged cross-sectional view taken on line 4—4 of Fig. 2.

Fig. 5 is an elevational view, with parts broken away and shown in section, illustrating the molding of the doffer assembly.

Fig. 6 is a cross-sectional view, similar to Fig. 4, of a modification of the doffer assembly of Figs. 1—4.

Referring now to the drawings, the doffer assembly includes an annular disc 11 having a central aperture 12 and a cylindrical hub 13 integral with the disc. The hub has an upwardly projecting portion 14 and a downwardly projecting portion 15 which is shorter. The hub is preferably toothed to provide driving means, but this feature forms no part of the invention. Surmounting the face of the disc are a plurality of lugs or doffer pads 16 which are integrally connected to the disc 11 and have a circumferentially spaced relationship. The lugs are located co-extensively with the outer surface of the disc at its periphery and are essentially rectangular in cross-section except for a beveled shoulder 17 at the upper and inner edge. The lugs are preferably made of a rubber or synthetic rubber material which is fairly hard, yet resilient enough to yield when struck. For this purpose it is found that a rating of about 60 Durometer hardness is satisfactory. In contrast to this material, the basic material of the disc is a medium hard natural or synthetic rubber of about 95 Durometer hardness which is fairly rigid, yet flexible enough to withstand the shock. The disc is therefore less flexible than the lugs, yet more flexible than metal discs of the prior art. It is this critical relationship between the hard, yet flexible disc, and the more flexible pads that contributes so highly to the desirable results attained.

The disc is further strengthened by means of two fabric rings 18 and 19, as best shown in Figs. 3 and 4. The rings are composed of a woven fabric made of natural fibers such as cotton, artificial fibers such as nylon, rayon,

or dacron, or any combination thereof. One particularly effective fabric has been made by using a nylon-cotton combination. The fabric is also preferably coated with a natural or artificial rubber to provide a better seal with the disc. The rings are coextensive with the outer periphery of the disc and extend partially inward thereof, but do not extend to the inner periphery thereof to eliminate the possibility of cracking at the hub. The upper ring 18 extends further toward the center than does ring 19 in order to minimize cracking at their inner surfaces.

The bonded relationship of the disc 11, the fabric rings 18 and 19, and the lugs 16 is better understood with reference to Fig. 5 in which the molding apparatus is illustrated. A lower mold 20 has a central aperture and is shaped at 21 to accommodate the upper portion 14 of the hub 13 at its inner portion. The mold is also shaped at 22 to receive each of the lugs 16 at its outer periphery as shown. As can be seen, the mold is designed to form the doffer assembly in an upside-down position, in order that the lugs may be held in place. The lugs are then placed in the space 22 of the mold and the hub 13 is placed in the space 21, and the upper fabric ring 18 is laid upon the lugs as shown. The disc 11 is then placed atop the ring 18, with the inner periphery in contact with the hub, and the lower ring 19 is placed atop the disc. A central retainer pin 23 is slipped inside the hub to maintain the inner diameter thereof to a close tolerance.

The doffer assembly is now in place, and the upper mold 24 is placed over the assembly. The two molds, it is noted, are not completely closed at this point, being separated by a gap 25 to permit compression. The inner portion of the mold adjacent its central aperture has a space 26 to accommodate the portion 15 of the hub. It is further noted that the inner surface of mold 24 is slightly tapered to provide for a slightly thicker root portion of the disc, thus providing added strength.

Upon completion of the above steps, heat and pressure are applied, as well known in the art, sufficiently to vulcanize and bond the components of the doffer. The gap 25 is closed to permit the mold surfaces to meet, thus forcing the fabric rings or layers into the disc and causing them to bond to the opposite surfaces of the disc. At the same time, the doffer lugs or pads are forced into the fabric ring 18 to form a unitary structure of the lugs, fabric, and disc. This process is aided by a slight increase in volume of the lugs which causes them to slightly depress the fabric ring. The line of bonding between each lug and its contacting fabric portion is inwardly arcuate in a peripheral direction; that is, when viewed from the outer periphery. This is best shown in Fig. 4. As a result, the center portion of the disc is actually below the upper surface of the disc. This provides for an unusually strong junction between the lugs and the disc to minimize the separation or cracking that might otherwise occur. Due to the flexible nature of the disc and fabric reinforcement with the flexible and well-anchored lugs, a highly effective doffer assembly is obtained. The relative flexibility of the components of the unitary doffer assembly eliminates the need for accuracy of the location of the lug elements and the need for a critical relation of the lug elements to the picker spindles of the cotton picking machines. If the relative timing of the contact between the doffer pads or lugs and the cotton picking spindles is off, the strength of the flexible pad element and the shock absorbing characteristics of the disc assembly insures that the load of the picker spindles will be accommodated without damage or permanent deformation of the doffer assembly and without damage to the spindles. The flexible lugs offer a primary shock absorbing action while the wholly flexible disc unit provides a secondary shock absorbing action to minimize load effects thereon.

To summarize the many advantages of the improved

doffer assembly as described with reference to the preferred embodiment herein, the assembly unit as afforded by the invention is highly efficient, durable and accordingly economical. It will be noted that the disc assembly, even in its reinforced condition, is flexible and the lug elements are relatively more flexible. The integral annular fabric rings at either face of the disc assembly insure a high degree of strength which is exceedingly adequate for application to spindles of cotton picking machines. The variation in width between the fabric rings 18 and 19 is critical since this feature has proven by extensive test to avoid any cracking at the lines of bond. The respective lugs in their molded relation to the sandwich assembly providing the composite disc are anchored in a highly improved fashion as pointed out. The relative flexibility of all the components of the invention assembly provided will significantly reduce the normal wear of the lug elements and insure a longer life to the assembly thereby.

20 A modification of the preferred embodiment of the invention is shown in Fig. 6 of the drawings. As proposed therein, the assembly consists of a disc 31 and rubberized fabric rings 32 and 33 which are integrally connected to the respective faces of the disc in the manner provided in the preferred embodiment of the invention. However, in this instance lugs 34 are seated on the fabric ring 32 so as to provide a planar connection therebetween at the outer face of the sandwich disc unit. The base of each of the lug elements is provided with fillets 35 30 molded integrally therewith and extending laterally thereof and also molded with and seated in integrated fashion to the fabric ring 32 at the working surface of the disc assembly. While the disc assembly is of the same composite structure as the preferred embodiment of the invention, the improved anchoring of the lugs is effected by lateral fillets which afford stabilization of the lugs relative to the flexible reinforced disc unit as they are integrated to the fabric band. This is in lieu of the anchoring effect of the preferred form, achieved by the 40 arcuate mold line of the fabric ring.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific 50 as to structural features, it is to be understood that the invention is not limited to the specific features shown, but that the means and construction herein disclosed comprise but a few of the several modes of putting the 55 invention into effect. The term "rubber" as used herein, and especially in the claims, is intended to refer to not only the natural rubbers, but to synthetic rubbers and combinations thereof which are well-known in the art.

We claim:

- 60 1. A doffer assembly comprising a disc of flexible rubber, reinforcing means formed integrally with said disc and providing crack retarding means therefor, and doffer lugs seated on and having the root portions thereof molded to said disc through said reinforcing means to provide a non-planar connection therebetween.
- 65 2. A doffer assembly including a flexible base element having fabric reinforcing means connected to at least one face thereof and flexible doffer lugs integral with said fabric reinforcing means to dispose the root portions thereof at least in partially depressed relation to seat within said base element.
- 70 3. A doffer assembly including a disc of relatively hard flexible rubber, flexible rubberized fabric element means connected to at least one face of said disc, and

doffer lugs integral with said disc through the medium of said fabric element means.

4. A doffer assembly including a flexible disc of rubber or the like, an annular section of rubberized fabric integrally connected to each opposed face of said disc, said fabric sections being of different widths, and doffer lugs connected to said disc through one of said fabric sections whereby said assembly will be resistant to cracking and tearing of lugs therefrom.

5. A doffer assembly including a base of a flexible nature, a fabric coating on at least a portion of said base, and doffer lugs bonded to said base through said fabric coating.

6. A doffer assembly including a disc, said disc having means providing a partial rubberized fabric coating adjacent its periphery and doffer lugs seated thereon, the base of said lugs being relatively depressed within and bonded to said coating.

7. A doffer assembly comprising a molded disc of flexible rubber or the like, flexible means molded to the surface of said disc at least adjacent its periphery providing strength therefor in order to prevent cracking or deformation, and flexible doffer lugs engaged integrally with said disc and said strengthening means.

8. A doffer disc comprising a flexible element of annular configuration having mounting means integral therewith, an annular member of rubberized fabric integral with each of the faces of said element extending inwardly from its periphery, said members being of different width, said element and members constituting a layered disc highly resistant to cracking and deformation under load.

9. A doffer disc comprising a flexible element of hard rubber, rings of fabric molded to the faces of said element and located at the outer periphery thereof, said rings increasing resistance of said element to cracking and deformation while maintaining its flexibility and doffer lugs having their roots mounted on and bonded to one of said rings.

10. A doffer disc assembly comprising a flexible element of medium hard rubber, a peripheral ring of fabric molded to one face thereof lending resistance to cracking and deformation on distortion while maintaining its flexibility, and flexible lugs molded into said element face to be bonded thereto through said ring.

11. A doffer disc assembly comprising a flexible plate element, peripheral rings of fabric molded to opposed faces thereof lending resistance to cracking and deformation to the plate element on distortion, and flexible lugs molded into one face of said plate element to be bonded thereto through said ring on said face, the roots of said lug being molded in recessed fashion to the outer surface of the composite unit to which they are applied.

12. A doffer disc assembly comprising a flexible element of rubber, annular rings of impregnated fabric molded integrally to opposed faces of said element, said rings lending resistance to cracking and deformation of the element upon distortion while maintaining its flexibility, and lugs molded into the ring on one face of said element, the root of each lug being non-planar in nature and the central portion thereof seating deeper than the end portions.

13. A doffer disc assembly comprising a flexible disc of rubber, annular rings of impregnated fabric molded integrally to opposite faces of said disc, and a plurality of circumferentially equally spaced lugs having a greater flexibility than said disc integrally bonded to one of said rings and the corresponding face of the disc, the portion of said ring bonded to said disc having an inwardly arcuate shape in a peripheral direction.
